UNITED STATES PATENT OFFICE.

LOUIS JOSEPH BARTHELEMY, OF SAN JUAN, PORTO RICO.

PREHEATING DEVICE FOR CONCENTRATING EVAPORATORS.

Application filed June 29, 1921. Serial No. 481,309.

To all whom it may concern:

Be it known that I, LOUIS J. BARTHELEMY, a citizen of the United States, residing at San Juan, Porto Rico, have invented certain new and useful Improvements in Preheating Devices for Concentrating Evaporators, of which the following is a specification.

The primary purpose and object of the present invention is to provide a juice heater and pre-heater for raw juices to heat the juice for the effects, or pans, of the apparatus in which it is subsequently subjected to a process of evaporation.

15 A further object is to provide means for utilizing the vapors, of the several bodies or evaporating pans of the apparatus, for pre-heating raw juices and for making use of the hottest, and ordinarily wasted, vapors in the initial heating of the cold juices.

An additional object is to provide a juice heater which may be installed and built up in the evaporating apparatus to any desired capacity, or which may be used separately 25 in one or more of the evaporating pans, as the case may require.

In general, the invention purports to provide a juice heater of the character inferred which will enable the evaporating apparatus 30 to do more work, increasing the capacity of the plant, and, at the same time, reducing the fuel consumption.

With the above and other objects in view, the invention may be said to reside generally in the details of construction, combination and arrangement of parts as will be herein-after more fully pointed out and described, reference being had to the accompanying drawings, wherein—

40 Figure 1 is a front elevation of a standard quadruple effect, or evaporating pans, of a sugar manufacturing apparatus, illustrating the manner of applying a heater of the double stage thereto, the heater being in section, said section taken on the line X—X of Figure 3.

Figure 2, a vertical sectional view of a single effect, with a heater of the single stage applied thereto, the heater being in section, said section being taken substantially on the line X—X of Figure 3.

Figure 3, a diagrammatic view of a heater, showing the arrangement of tubes and compartments, and

Figure 4, a sectional view of a double 55 stage heater, showing the location and arrangement of upper and lower tubes and compartments, or stages, the compartments being in section, said section being taken on the line X—X of Figure 3.

This invention is adapted to be used in connection with an apparatus for making sugar from sugar-cane and, by way of preface, it may be well to set forth briefly, and in a general way, the operation and

construction of this apparatus which, however, is well-known to those skilled in the art and need not, therefore, be fully set forth in detail herein. That particular portion of the apparatus with which the invention

is immediately associated, is, however, illustrated in the accompanying drawings, and comprises a quadruple effect or evaporator wherein the juice of the sugar-cane is treated to a process of evaporation. The evaporator consists of a number of bodies or pans,

20 as indicated at 5, 6, 7 and 8, each of which include a steam-belt 9, a vapor-belt 10 and a dome 11. Beginning with body 5, the dome of each pan is connected, by a pipe so

not shown, to the vapor-belt of the succeeding pan; the dome of the last body, however, being connected up with a condenser, not shown, in the usual manner. Ordinarily, in the manufacture of sugar, the

35 raw juice is extracted from the materials, as by passing the sugar-cane through a mill, and after defecation, is discharged into the filtering tank where the scum and other refuse is separated and carried away. From

the filtering tank the juice is pumped through one of the ports 12 into the first pan 5 of the four pans constituting the quadruple effect and part of the water is evaporated. Thence it is led to the second

45 pan 6 and from there to the third pan 7, and thence to the fourth pan 8. In each successive pan, a portion of the water is evaporated. Each pan is heated by steam supplied to its steam-belt and the vapor arising from the juice is led, in the first instance, upwardly through the dome of the

first body from whence it is conducted to the vapor-belt of the second body 6 and supplies heat for further evaporation of the juice contained within such body. In like manner the vapor from each body is successively utilized in every succeeding body up to the last which is connected to the condenser. A large percentage of the water in the juice is thus evaporated in the quadruple effect, leaving the sirup, as it is then called, in a much concentrated condition. After passing out of the last pan the sirup is clarified and subsequently passed to the vacuum pan, not shown, where the final evaporation takes place. However, the vapors after leaving the last or fourth pan 8, and also the vacuum pan, previously mentioned, pass on to the condenser at a very high temperature and ordinarily constitute a great loss and waste in heat. Moreover, a very large volume of water is required to condense such vapors which are very valuable as a fuel.

By means of the present invention, however, it is possible to utilize the heat of these vapors to the maximum extent and to reduce the temperature of the vapors going to the condenser so as to require less water to be used in the condenser. In other words, the invention enables the raw juice to be heated before it is subjected to the evaporating process usually carried on within the evaporating pan. It embodies a heater which may be made into a single integral structure, or made into sections bolted or otherwise fastened together, and may also be built in one or as many more stages as may be desired when a large capacity is required.

In its simplest form or single stage, the heater comprises a cylindrical tube or drum 13 having annular flanges 14 and 15 provided each with an endless series of bolt or rivet holes 16. Integrally associated with the drum and formed upon the inner wall thereof so as to be centrally located between the open ends, is a plurality of closed compartments 17, arranged in pairs connected by a communicating passage 18. A similar arrangement of compartments 19 is had on the portion of the wall immediately opposite. The compartments of each series are closed by an upper wall 20 and a lower wall 21 while the front or inner wall 22 serves as a tube sheet and is accordingly pierced with a suitable number of openings, either five, eight or more, according to the number required. The tubes, indicated at 23, are supported crosswise of the drum, as shown in Figure 3, and in groups between the two series of compartments; the ends of the tubes being inserted through and expanded behind the tube sheet of opposed, corresponding compartments. Each group and the tubes thereof, are all relatively spaced to provide for passage between them and through the

drum when the heater is in place on the evaporator. On opposite sides the drum is provided with short pipes, each of which constitutes an inlet or outlet for one of the series of compartments as found most convenient, since the juice can be entered on either side. The juice enters the drum on one side through the inlet pipe, indicated in the drawings at 24, and circulates back and forth through the tubes of each group, passing from one compartment to the other until discharged through outlet 25 on the other side. Each compartment can be provided with a suitable hand hole and cover to permit the cleaning of the tube or to permit the detaching and replacing of leaky tubes.

In its more elaborate form the heater may include as many stages or groups of compartments and tubes, as may be desired for increasing the capacity of the device. In Figure 4, a heater of the double stage is illustrated. This, as shown, is quite similar in construction to the single stage heater previously described, and shown to advantage in Figure 2 of the drawings. In fact, the double heater differs from the other only in that it consists of a unit having two separate and distinct sets of compartments and tubes arranged one above the other, as shown in Figure 4, and providing, respectively, an upper stage 27 and a lower stage 28. Connecting the two stages and providing a passage from one to the other is a conduit 29 having a flow-control valve 30 and a drain valve 31 provided therein for the purposes indicated. The juice enters the heater through the inlet 32 of the lower stage and after circulating back and forth through the latter is conducted to the upper stage from which it is subsequently discharged through outlet 33. The openings indicated are for the rivets or bolt fasteners 35 whereby the heater is secured to the flanges of the dome and vapor belt of the evaporator body to which it is applied.

To facilitate setting up the device and enabling it, also, to be shipped or otherwise transported without difficulty, the unit or heater of both single and double type may be built in sections, such as indicated at 36, 37 and 38, in Figure 3; the end sections 36 and 38 being bolted to the middle section as shown at 39.

In applying the invention to the apparatus, a heater or unit of either the single or double type is placed between the vapor belt 10 and the dome 11 of an evaporating pan or effect, being fastened to the flanges of each, as illustrated in Figure 2. Whether the heater be of a single or double stage, its general association and method of use with an evaporator pan is the same, and hence, the following remarks concerning the use and operation of the double stage heater may be taken to apply equally well to the single

stage type. As shown in Figure 1, in the general arrangement of the invention, a heater or unit is placed in only the fourth and first body of the quadruple effect but 5 units can be used in all of the bodies, should it be advisable to do so. A pipe 40 connects outlet 33 of one heater with inlet 32 of the other heater and is provided with a valve 41 at each end. The raw juice is pumped 10 through pipe 42 through the lower stage 28 of the heater in the last or fourth body 8 of the apparatus, passing back and fourth through the tube until forced through conduit 29 and into upper stage 27 from whence 15 it passes through pipe 40 into the heater of the first body or pan 5, entering the lower stage of the heater. After passing through the nest of tubes of the upper and lower stages, the juice is discharged from the heater 20 and conveyed through discharge pipe 43 to a defecator for settling, prior to its introduction into and subsequent subjection to the evaporating process within the bodies or pans in the usual manner. During the 25 usual operation of the apparatus the hot vapors arising from the steam heated juice within the vapor belt of the successive pans passes upwardly between and around the tubes of the heaters or units comprising the 30 invention, and serve to heat the juice flowing therethrough. The vapors of the first pan pass into the second pan and from there into the third, et cetera. In this manner it is 35 possible to utilize all the vapors from the several bodies; utilizing the vapors of the fourth or last body, which are deemed coldest and the ones most usually wasted, for heating the cold juice; that is, as first introduced into the heater. By thus using these 40 wasted vapors to first heat the raw juices there is a gain of the heat or temperature that is sent to be cooled by the condenser. The coldest vapors are utilized to heat the 45 juices at its coldest degree, as the heated juices come in contact with the hottest vapors. In this manner the high heat going from one body to another is maintained, which would not be the case if the cold juices were fed against the hottest vapors. 50 Besides, the raw juices coming in contact with the vapors that rise with the last body has tendency to carry off a certain amount in entrainment. Now, these globules when 55 coming in contact with the cold juices that are in the tubes of the heater will serve two purposes; the globules will be thrown back into the vapor belt and then the vapors will heat the juices to as high a temperature as possible. This is an important feature as it 60 will prevent entrainment, etc., heat the juices, and requires less water for the condenser.

By the addition of more heating units or 65 units with more stages, the area of heating surface may be increased and the capacity

of the heater raised. In this way, it is also possible to reduce the fuel consumption so that the work of sugar centrals can be done with bagasse alone, as other heaters, now in use in all factories, using the exhaust steam 70 will not have to be used after the effects are started in operation. More heaters can be added, if desired, both in the fourth, third and second bodies, so that all the juices may 75 be heated before entering the effect, and the temperature of the juice raised to the boiling point before it enters the first body for evaporation. This will enable the bodies or pans to do more work, and thereby increase the capacity of the plant. It is to be noted 80 that the juices are passed through the lower stage first and then sent through the upper stage. This is done to keep the tube always well filled. Two, three or more of the units 85 of the single stage type may be used together, if desired, to provide a heater of increased capacity, and when mounted, one above the other and fastened in place between the vapor-belt and dome of an effect, will have the desired amount of heating surface to 90 suit the capacity of the plant. Both single and double types of heaters can be used interchangeably. With a unit of two stages the heating surface is doubled and at less 95 cost than if two single stage units are used for the same amount of heating surface, hence, its use is preferred in plants of large capacity although more expensive. In placing the units between the vapor-belt and the dome, the joints are made with putty as this 100 gives no trouble, and the number of tubes in each group or stage will be governed by the capacity required to handle the juices from the total amount of ground cane, as 105 all the raw juices must pass through the tubes.

From the foregoing it will be seen that the invention provides a heater and pre-heater for the raw juices, which is economical in construction and so designed as to make use 110 of the vapors from the various pans and effects of evaporating apparatuses of various types, it being here mentioned that the invention is equally applicable to all standard effects, whether they be of the horizontal or vertical type. I desire it to be understood that I may make such changes in the construction, combination and arrangement of parts, materials, dimensions, et cetera, as 115 may prove expedient and fall with the scope 120 of the appended claim.

Having thus described my invention, what I claim as new and desire to secure by Letters Patent is:

The combination with a liquor evaporator 125 comprising a steam belt, a vapor belt and a dome, of a preheating device for the liquor disposed between the vapor belt and dome comprising a cylindrical drum, a set of compartments disposed on one side of the evapo- 130

rator, a similar set of compartments disposed on the opposite side of the evaporator, the compartments of each set being arranged in stepped relation relative to each other, tubes connecting oppositely disposed compartments, the alternate compartments on the same side communicating, whereby a zig-zag passage is formed, and an inlet and an out-

let for the liquor communicating with the end compartments of one set. 10

In testimony whereof I affix my signature in presence of two witnesses.

LOUIS JOSEPH BARTHELEMY.

Witnesses:

JUAN VALDYAR,

JANVIL STEVNSON.
